UNITED STATES PATENT OFFICE.

VIO R. HACKETT, OF DEXTER, NEW MEXICO; GRAYCE FAHRELENDER ADMINISTRATRIX OF SAID HACKETT, DECEASED.

SHOE PROTECTOR.

Application filed November 6, 1923. Serial No. 673,114.

This invention relates generally to the shoe art and has more particular reference to an attachment for shoes in the form of a sheet metal plate for the application to the 5 instep of a shoe for protecting the same from cuts and the like when the foot of the user is employed for forcing a spade or shovel into the ground, it being of course apparent that this attachment is to be specifically employed in conjunction with workmen's shoes.

The primary object of this invention resides in the provision of such a protecting attachment for shoes that may be manufactured and marketed at small cost and one that may be readily applied to the shoe in a simple and ready manner.

With the above general objects in view and others that will become apparent as the 20 nature of the invention is better understood, the same comprises the novel form of a shoe protector hereinafter more fully described, shown in the accompanying drawings and claimed.

25 In the drawing wherein like reference characters indicate corresponding parts throughout the several views:—

Figure 1 is a side elevational view of my shoe attachment applied,

30 Figure 2 is a bottom plan view thereof, in its applied form, and

Figure 3 is a plan view of the blank from which this shoe protecting attachment is formed.

35 Now referring to the drawing in detail, my novel protector for workmen's shoes comprises a substantially rectangular-shaped plate 5 of suitable metal that is provided adjacent one end with openings 6 whereby this end of the plate may be rigidly secured to the sole *a* of the shoe *A*, at a point adjacent the instep portion thereof through the medium of suitable rivets 7. This plate is then bent upwardly into close contact with 40 said instep portion of the shoe, the rear end of this plate adapted to be bent downwardly upon the fold line 8 for closely contacting the same with the front edge of the shoe heel *B*, Figure 1.

45 This downwardly bent portion of said plate 5 which is indicated by the reference

character 9 is formed with a rearwardly extending portion 10 said rearwardly extending portion being formed by further bending the blank shown in Figure 3 upon the 55 fold line 11. This rearwardly bent portion 10 of said blank 5 is formed with a desirable number of teeth 12 for biting engagement with the shoe heel *B* which serves as an additional means for securing said attachment plate to the instep of the shoe.

Upon opposite edges of this plate 5 and intermediate the ends thereof, are laterally extending integral ears 13 which after the plate has been properly applied to the instep 65 of the shoe are bent upwardly and then inwardly upon the fold lines 14 and 15, respectively for engaging around the edges of the instep portion of the shoe sole *a* for also maintaining the plate attachment in proper 70 engagement with the shoe.

It will thus be seen that I have provided a highly novel and useful form of protector for the insteps of workmen's shoes, and one that will, I believe, meet with all of the requirements for a successful commercial use.

75 Minor changes may be made within the invention without departing from the spirit and scope of the appended claim.

Having thus described my invention, what 80 I claim as new and desire to secure by Letters Patent, is:—

A shoe sole and heel protector comprising an elongated plate arched to conform to that portion of the sole with which it coats, 85 and having an end portion directed downwardly at right angles to the body portion and adapted to cover a portion of the front face of the heel, the lower edge of said downwardly directed portion being equipped 90 with rearwardly directed prongs adapted to be embedded in said heel, said plate being plain on opposite faces, formed at its forward end with apertures for passage of fastenings, and provided on its opposite longitudinal edges with upwardly directed ears, the extremities of which are adapted to be bent inwardly toward each other and clinched against the upper side of said sole.

95 In testimony whereof I affix my signature.

VIO R. HACKETT.
